HAIR CURLER

Alexis Zachary, New York, N. Y.

Application November 30, 1950, Serial No. 198,432

2 Claims. (Cl. 132—33)

1

This invention is an improvement in hair curlers for use in permanent waving, and particularly a curler for setting the hair in ringlets to facilitate the further treatment which is given to enable the ringlets to retain their shape.

It is an object of my invention to provide a simple and effective implement for operating upon the hair in tufts, each comprising a number of separate locks, and impart thereto the form desired.

The invention is clearly set forth in the ensuing description, taken with the drawings, which illustrate the preferred embodiment of the invention.

On the drawings:

Figure 1 is a side view of the implement.

Figure 2 is a side view of the same implement in Figure 1, turned through ninety degrees.

Figure 3 is a partial section on line 3—3 in Figure 1.

Figure 4 is a cross section on line 4—4 in Figure 3.

Figure 5 is a view of part of the device seen from the right of Figure 1, with part omitted from the outer end.

Figure 6 is a side elevation showing part of a modified form of the device.

Figures 7, 8 and 9 show clamps used in the curling operation; and

Figure 10 is a side elevation showing the device with a tuft of hair wound upon it, and the post detached.

The body of the curler is a round stem or rod 1 having at one end a fixed tubular head 2.

Attached to the head in longitudinal position is a comb 3. The rod or stem is hollow over a great part of its length and has a spring 4 in a bore 5 extending from said end inward. At each side the hollow portion of the rod has slots 6 open through said end. On the outside of the body 1 is a sliding head 7 having on the end presented to the fixed head 2, a flange or rim 8.

The head 7 carries a pivoted clip 9 which is transversely curved so that it conforms to the shape of the rod 1. This clip has arms 10 which extend half way around the stem 1 and are perforated at the ends to receive a pivot pin 11. This pin passes through the slots 6 and the inner end of the spring 4 seats against the pin 11. The clip when folded against the rod 1, with the pin 11 at the inner ends of the slots 6, has its free end flush with the extremity of the rod opposite the extremity carrying the head 2 and comb 3.

The sleeve or head 7 has a fixed extension or shank 12 at the flange 8, projecting toward the head 2. The outer end of the bore 5 in the rod

1 is closed by a plug or closure member of rubber 13 which is elastic and assists the resiliency of the two portions 14 of the rod, divided by the slots 6, to hold these portions apart. The head 2 has a space or slot 15 open to the extension 12, and this extension is preferably tapered towards the outer end and rounded on the edge so that it can easily be slipped into the space 15. When the sleeve 7 is moved to insert the extension 12 as far as it will go, the portions 14 of the rod 1 are compressed slightly, but when the extension is pulled out the rubber 13 expands and the portions 14 move back to normal positions. The rubber ensures a tight fit of the extension 12 in the head 2.

The clamps of Figures 7, 8 and 9 each have a pair of jaws 16 and 17 with lugs 18 connected by pivot pins 19. At one end are the handles 20 between which is mounted a fixed compression spring which acts to separate the handles and move the jaws toward each other. The jaw 16 as shown in Figure 7 has prongs 21 between which is a blade 22, and the jaw 17 is flat, as indicated at 23, with its surface at right angles to the blade 22. The blade 22 can be omitted, or this blade retained and the prongs 21 omitted as indicated in Figures 8 and 9. The rod 1 and clip 9 can be made each with a notch 24 in the end remote from the head 2, as indicated in Figure 6.

In practice the attendant smooths out a tuft of hair with the comb 3; first pushing the sleeve 7 to force the extension 12 into the space 15. The opposite end of the rod is then put into contact with the subject's scalp and the clip 9 is first raised. The end of tuft 25 is secured to the rod 1 by laying the clip 9 against it, and the rod is turned to wind the hair upon the rod. The ringlet or curl is now engaged by one of the clamps, such as the one shown in Figure 7 or 9, with the flat jaw 23 under the adjacent end of the rod 1 and the blade 22 in the recesses 24. The body of the curler is then removed, but the ringlet is compressed and held by the clamp, and it can then be given the usual treatment with lotion and washed with water to complete the process. The jaw 23 is wide enough to span and cover the recesses 24 in the rod 1 and clip 9, or it may enter the recess.

When the clamp is made without the blade 22, as in Figure 8, the recesses 24 in the rod 1 and clip 9 are not needed and they can be omitted. Instead of clamps I can even use hair pins, but these are not so easy to manipulate.

The implement is thus well adapted to serve its

purpose and gives excellent results. My invention is of course not limited to the exact details of construction, but may be varied in any respects without changing the general design of the curler.

The spring of the clamp is shown at 26, coiled around the pivot pin 19. Instead of a spring a rubber sleeve enveloping the clamp about at the base of the prongs 21 can be employed.

Having described my invention, what I believe to be new is:

1. An implement for treating hair comprising a rod-shaped body, a head on one end, the body having a bore extending into it from said end, slots in the sides open at said end, a compressible element in said bore at said end, the head enveloping said end, a closure member in the bore at said end and engaging the adjacent extremity of the compressible element, a sleeve movably mounted on the body, a clip on the sleeve, a pivot pin extending through the bore and projecting through said slots, the ends of the clip being engaged by the pin, the inner end of said element abutting said pin. 15

2. An implement for treating hair comprising a rod-shaped body, a head on one end, the body having a bore extending into it from said end, slots in the sides open at said end, a compressible 25

element in said bore at said end, the head enveloping said end, a closure member in the bore at said end and engaging the adjacent extremity of the compressible element, a sleeve movably mounted on the body, a clip on the sleeve, a pivot pin extending through the bore and projecting through said slots, the ends of the clip being engaged by the pin, the inner end of said element abutting said pin, said sleeve having an extension, the implement having a space under the head to receive said extension when the sleeve and clip are moved on the body towards the head. 10

ALEXIS ZACHARY.
